UNITED STATES PATENT OFFICE.

JOHN W. MAILLOT, OF NORTH ATTLEBOROUGH, MASSACHUSETTS, ASSIGNOR
TO THE F. M. WHITING COMPANY, OF SAME PLACE.

DESIGN FOR A SPOON.

SPECIFICATION forming part of Design No. 24,417, dated June 25, 1895.

Application filed March 29, 1895. Serial No. 543,756. Term of patent 3½ years.

To all whom it may concern:

Be it known that I, JOHN W. MAILLOT, a citizen of the United States, residing at North Attleborough, county of Bristol, State of Massachusetts, have invented and produced a new and original Design for Spoon-Handles and the Like, of which the following is a specification.

In the drawing the figure shows a plan view of the handle as applied to a spoon.

The leading feature of the design is in the surface ornamentation and configuration of the handle.

The bowl of the spoon is shown at A and from this extends a handle B. A heart C projects from the upper end of the handle from

which extends a floral wreath D inclosing the representation of a foot. The ends of the wreath terminate in a bow and the end of the ribbon entwines the handle as at E. On the spoon handle is an open space for any suitable word or letters.

I claim.

The design for a spoon or other handle herein shown and described.

In testimony whereof I affix my signature in presence of two witnesses.

JOHN W. MAILLOT.

Witnesses:

WILLIAM H. POND,
LOUIS E. MORSE.
